UNITED STATES PATENT OFFICE.

THOMAS A. TEATE, OF THOMASVILLE, GEORGIA.

ROTATING LIGHT FOR RAILROAD-CARS.

968,714.

Specification of Letters Patent. Patented Aug. 30, 1910.

Application filed June 5, 1909. Serial No. 500,330.

To all whom it may concern:

Be it known that I, THOMAS A. TEATE, a citizen of the United States, residing at Thomasville, in the county of Thomas and 5 State of Georgia, have invented a new and useful Rotating Light for Railroad-Cars of which the following is a specification.

This invention relates to locomotive head-lights and the object of the invention is to 10 provide a simple mechanism by which the headlight will be turned so as to throw the light to one side when the locomotive is rounding a curve.

The invention consists in certain novel 15 features of the same which will be herein-after first fully described and then particularly pointed out in the appended claim.

In the annexed drawings, which fully 20 illustrate the invention, Figure 1 is a side elevation of the improved headlight and so much of the locomotive as is necessary to furnish a complete understanding of the invention. Fig. 2 is a plan view of the same. Fig. 3 is a vertical transverse section taken 25 on the line 3—3 of Fig. 2. Fig. 4 is a detail view of a modification.

The locomotive, indicated generally by 1, is of the usual or any preferred type and the headlight 2 is mounted at the front end 30 or the same upon a shelf or other support 3, being carried by a shaft or journal 4 rotatably mounted on the said shelf and fixed to the bottom of the headlight, as will be readily understood. At its upper end, or 35 other convenient point, the headlight body is provided with a segmental gear 5 which is in mesh with a driving gear 6 carried by the front end of a rock shaft 7 which is journaled in suitable standards or brackets 40 8 rising from the locomotive boiler in advance of the smoke stack. Between the standards or brackets 8 a heavy weight or pendulum 9 is suspended front and carried by the rock shaft 7 by means of hangers 10 45 which are extended upward from the weight and pass through the said shaft and are secured thereon by nuts 11, as clearly shown in Figs. 1 and 2. These hangers or bolts 10 are provided with headed lower ends and 50 the weight is cast around the same, as will be readily understood on reference to Fig. 3. Said view also shows the peculiar shape which I give the weight 9, curving its sides downwardly and outwardly to produce shoulders 55 9^a and to bring its center of gravity low beneath the shaft 7, and rounding its lower

face transversely as shewn at 9^b. In order to retard the movement of the weight so as to impart steadiness to the device, I provide springs imparting a nearly vertical pressure upon the weight, and these springs I have shown in the drawings in two forms. Those lettered 12 are secured upon the locomotive at one end and their free ends 12^a bear downward upon the shoulders 9^a. In Fig. 4 I have shown a spring 13 also secured at one end upon the locomotive and bearing upward near its free end against the rounded lower face 9^b of the weight. These views are merely illustrative of my idea, however, 70 which is that I prefer to have the free end of the spring or springs press upon the weight in a nearly vertical direction, instead of horizontally against its sides.

From the foregoing description, taken in 75 connection with the accompanying drawings, it is thought the operation and advantages of my improved headlight will be readily understood and appreciated. It being the common practice to build railroad curves 80 with the outer rail in a higher plane than the inner rail, the locomotive will lean over the inner rail in rounding a curve. As a result of this inward leaning of the locomotive the pendulum weight 9 will swing 85 toward the same side and will thereby rock the shaft 7 and impart motion directly to the driving gear 6 which in turn will actuate the segmental gear 5 and thereby turn the headlight on its journal or supporting shaft 4 so that the light rays thrown from the lantern will be projected to the inner side instead of passing off beyond the curve as with the ordinary stationary headlight. As the weight is hung beneath a horizontal 90 shaft standing longitudinally of the locomotive it can swing only from side to side, and as it begins to swing in either direction it starts out by moving horizontally and then of course rises on a curved line. In the 100 ordinary vibration which takes place, even on a level track, the weight will swing very easily a little from its normal central position with the result that the headlight will be constantly turned from side to side. To 105 overcome this device have heretofore been constructed having springs exerting a constant inward pressure on a horizontal line toward each other on the sides of the weight so that when the latter moved ever so little 110 one spring was compressed and the other allowed to expand. By my invention I

avoid vibration with the use of springs, but I mount the latter so that their extremities bear downward on the weight as in Fig. 3 or upward thereon as in Fig. 4, with the result in either arrangement that the first or horizontal movement of the weight in either direction causes it to slip frictionally along the spring rather than to compress the latter, although further movement of the weight will compress it as can be seen. It follows then that such mounting of the springs retards the movement of the weight by friction at first and by the resiliency of the spring later. As the locomotive assumes its normal position the pendulum will, of course, return to its normal position and this return movement will be accelerated by the springs 12, as will be readily understood.

20 The device is composed of very few parts and is free from complicated arrangements so that it will operate with certainty and will prove efficient for the purpose desired.

Having thus described my invention, what I claim is:—

25

The combination with a locomotive, a headlight mounted on an upright pivot thereon, a horizontal rock shaft mounted in standards on the locomotive, and gearing between the shaft and headlight; of hangers 30 depending from the shaft, a weight rigidly secured to them and having outwardly curved sides forming upwardly facing shoulders and a rounded lower face so that its center of gravity is low, and a spring secured at one end to the locomotive and bearing near its free end against the weight in a substantially vertical direction, for the purpose set forth.

35

In testimony that I claim the foregoing 40 as my own, I have hereto affixed my signature in the presence of two witnesses.

THOMAS A. TEATE.
